UNITED STATES PATENT OFFICE.

HERMAN A. POPPENHUSEN, OF HAMMOND, INDIANA, AND ARTHUR P. STRONG, OF CHICAGO, ILLINOIS, ASSIGNORS TO GREEN ENGINEERING COMPANY, OF EAST CHICAGO, INDIANA, A CORPORATION OF ILLINOIS.

VALVE MECHANISM FOR ASH-CONVEYING OR LIKE SYSTEMS.

1,393,905.

Specification of Letters Patent.

Patented Oct. 18, 1921.

Application filed February 21, 1919. Serial No. 278,351.

To all whom it may concern:

Be it known that we, HERMAN A. POPPENHUSEN, a citizen of the United States, residing at Hammond, in the county of Lake and State of Indiana, and ARTHUR P. STRONG, a citizen of the United States, residing at Chicago, in the county of Cook and State of Illinois, have invented new and useful Improvements in Valve Mechanisms for Ash-Conveying or like Systems, of which the following is a specification.

This invention relates to an ash conveying or like system of the type wherein the material is moved through the conveying conduit or pipe line pneumatically by means of a motive fluid, such as steam, introduced into the conduit at several points in the length thereof.

Among the objects of our invention is to provide means operable from one or more points in the length of the pipe line, as for instance at the ash intake openings, so that the motive fluid may be turned on and off by a workman at the place where the ash or other material is being fed into the system, and thus require the use of the motive fluid only during the intervals while the material is being handled by the system.

The invention consists further in the several features of construction and combination of parts hereinafter set forth and described.

In the accompanying drawings—

Figure 1 is a side elevational view of a conveyer conduit of an ash conveying or like system equipped with a mechanism embodying the features of our invention;

Fig. 2 is an enlarged vertical sectional view taken on line 2—2 of Fig. 1.

Fig. 3 is an enlarged vertical sectional view taken on line 3— of Fig. 1;

Fig. 4 is a similar sectional view taken on line 4— of Fig. 1; and

Fig. 5 is a like sectional view taken on line 5—5 of Fig. 1.

In Fig. 1 of the drawings, we have shown the rear wall 1 of a battery of steam boiler or other furnaces, the ash-pits thereof being provided with discharge passages 2 opening outward through said wall; there being one discharge passage 2 for each ash-pit, and all in the arrangement illustrated being spaced the same distance above the floor 3 of the

furnace room and in horizontal alinement. The ash conveying system employed comprises a conveyer conduit formed of a plurality of metal pipes 4, 4 connected together end to end and arranged so as to have a lower horizontal section 5 in front of the rear wall 1 but below the discharge passages 2; a riser or vertical section 6 connected at its lower end with the horizontal section 5 by an elbow or like fitting 7; and an upper horizontal section 8 connected with the upper end of the riser 6 by an elbow 9. Said upper section 8 leads to a tank or hopper usually located outside of the building and into which the ash or other material handled by the pipe line is discharged for ultimate disposal. For moving the ash or other material through the conveyer conduit pneumatically, a motive fluid, such as steam, is introduced into the pipe line at the points required and discharged thereinto in the direction of movement of the material therethrough. The motive fluid is supplied from a suitable source and when steam is used it is usually supplied from the boilers of the furnaces with which the system is used. In the installation shown, a pipe 10 conveys steam to the ash handling system and is provided with a manually operable valve 11, to which is connected a depending rod 12 provided at its lower end with an operating handle 13 whereby the main supply of steam to the system may be turned on or shut off when desired. Said pipe 10 leads to a steam nozzle or jet 14 provided in the upper elbow 9. There is a like nozzle 15 in the lower elbow 7, which nozzle is connected with the pipe 10 by a branch pipe 16, the latter being coupled with the pipe 10 between the nozzle 14 and the valve 11, so that when the valve is closed the supply of steam to both nozzles is shut off. The lower horizontal section 5 of the pipe line may be supported above the floor 3 to the height required by any suitable means one form of which, as shown in the drawings, comprises upright standards 17 secured to the floor and provided at their upper ends with concave rollers 18, upon which certain of the pipes rest. The section 5 is provided with a plurality of ash intake openings 19 (Fig. 2), one located at each discharge passage 2, as shown in Fig. 1. Each ash intake opening 19 is formed by the

provision of a suitable hole in the pipe 4 and an intake saddle 20 having a top flange 21 extending to and in alignment with the bottom wall 22 of the discharge passage 2, 5 as shown in Fig. 2, so that the ash, when collected on said bottom wall, may be hoed or otherwise moved directly into the intake opening. The saddle is secured to its pipe 4 by U-bolts 23. Each intake opening 19, 10 when not in use, is closed by a removable plug or cover (not shown).

To enable the supply of motive fluid or steam to be under the control of the workmen from any one or more points in the 15 length of the pipe line, as for instance at each intake opening, so that the steam may be turned on and off by a workman while feeding ashes into the conveyer conduit, and thus use the steam only during such intervals, we provide a means whereby these 20 objects may be accomplished. One form of such means is shown in the drawings and is constructed as follows. Located in the steam pipe 10, between the main valve 11 and the branch pipe 16, is a valve 24 preferably of the gate type, although any other type of valve found desirable may be used. Said valve has an operating arm 25 connected between its ends with the rotatable 25 part 26 of the movable valve gate 24^a. At one end of the arm 25 is a counter-weight 27, adjustably connected with the arm if desired. To the opposite end of the arm 25 is connected a cable 28. When the arm 25 occupies the position shown in full lines in 30 Figs. 1 and 5, the valve 24 is closed and the supply of steam to the pipe line is shut off. On the other hand, when the cable 28 is pulled downward, the weighted end of the 35 arm 25 is raised and the valve 24 opened, thus allowing steam to be supplied to the pipe line, the parts when in such position being indicated by dotted lines in Fig. 5. Upon releasing the pull on the cable 28, the 40 counter-weight 27 drops and effects the closing of the valve 24 automatically, the weight of said counter-weight being sufficient to overbalance the weight of the cable and its connected parts, to be presently described.

45 Located adjacent each ash intake opening 19 and below the same is a depressible member in the form of a pedal 29, connected at its inner end by hinges 30 with the floor 3 of the furnace or boiler room. Beneath each 50 pedal are coiled springs 31, 31, which serve to hold the outer or free end of the pedal normally elevated or raised. The cable 28 extends downward from the valve 24 to the horizontal section 5 of the pipe line and has 55 a portion extending along said section 5 to the pedal 29 which is farthest from the riser 6, as shown in Fig. 1. The end of the cable at such pedal is directly connected therewith, as shown. To support and guide the cable, 60 we provide sheaves or grooved pulleys 32

clamped to the pipes in the section 5 at a plurality of points by pipe clamps 33, each having a split collar 34 clamped around the pipe section 4 and a fixed stud 35, upon which the pulley 32 is loosely journaled. A 70 strap member 36 is secured to the split collar and extends about the pulley and engages the outer end of the stud for preventing the pulley from being displaced off of the stud and the cable 28 from riding out 75 of the groove in the pulley. The cable 28 is further supported and guided by segmental plates 37, each being provided with a hole 38, through which the cable passes, as clearly shown in Fig. 3. Said plates 37 are secured 80 to the section 5 at the abutting ends of certain of the pipes 4, 4 thereof, by being clamped to the radial lugs 39 at the abutting ends of such pipes by the bolts 40, which engage said lugs for coupling the pipes together. 85 All of the other pedals 29, except the one farthest from the riser 6, are connected with the cable 28 by relatively short cable sections 41, which extend upward from the pedal over the associated pulleys 32, and coupled 90 or connected with the main cable 28 at about the points 41^a by suitable couplings provided for that purpose. The pedals 29 may be made in any form found most desirable for each installation, but, as shown in the 95 drawings, each pedal is made in the form of an open frame having two side members 42, 42, each being hinged to the floor 3 at its inner end by one of the hinges 30, and connected together at their free or outer ends 100 by a cross-piece 43 forming a foot-board. As illustrated, there is a pulley 32 directly above one of the side members 42 of each pedal, and the cable section trained over such pulley extends downward to such side member 42 and is connected therewith by a staple or U-bolt 44 (Fig. 2).

When no ashes are being fed into the pipe line, the valve 24 is maintained closed by the counter-weight 27, thereby shutting off the 110 supply of motive fluid to the system. When ash has been collected in one or more of the discharge passages 2 in proximity to the associated ash intake 19, the workman standing on the floor 3 in front of the discharge 115 passage steps on the pedal 29, depressing the same (see dotted lines in Fig. 2), and opens the valve 24 through the medium of the cable 28, as is apparent, thereby turning on the steam supply to the nozzles 14, 15. With 120 his foot maintaining the pedal depressed, the workman reaches over the pipe line into the passage 2 and hoes the ash into the associated intake opening 19. After he has fed the ash into the intake opening 19, he 125 releases the pedal 29, the latter being raised by the springs 31, and the valve 24 by the action of the counter-weight closes and thus shuts off the steam supply. It follows, 130 therefore, that the steam is consumed only

during the interval needed and at no other time. It makes no difference at what discharge passage 2 the workman may be employed, he always has within convenient reach means whereby he may turn on the steam supply and maintain it turned on as long as he is feeding ashes into the pipe line, and automatically shut off the steam when such work is completed. The enormous saving of steam is very marked, because in systems as heretofore used it has been found that ash handlers will turn on the steam and allow it to pass through the conduit for several hours, whereas they only feed ashes to the system for a relatively short period of time. The balance of the time while the steam is being needlessly consumed the workmen are resting or are going from ash-pit to ash-pit, or find it necessary to hoe ashes from a distance or break up clinkers preparatory to hoeing the ash into the discharge passages 2 in close proximity to the ash intakes 19. The steam is not shut off during the time that the system is idle because the valve 11 is at one point remote from the place where the ashes are handled and inconvenient of ready access. With our invention these objections are readily overcome, as is apparent, as the means described enables a workman to control the steam or motive fluid from any one of a number of points in the length of the pipe line without operating the main valve 11.

While we have shown and described herein in detail one form of a mechanism embodying the features of our invention, it is of course to be understood that the details of construction and arrangement of parts shown may be variously changed and modified without departing from the spirit and scope of our invention; and further a system equipped with our invention may handle other materials and is not necessarily confined to handling ashes.

We claim as our invention:

1. In an ash conveying system, the combination of a conduit having a plurality of ash intake openings, means for supplying motive fluid to said conduit for moving the material therethrough, means for controlling the supply of motive fluid to said conduit, including a member adjacent each ash intake opening and enabling the operator when at any one of the intake openings and while moving ash into the same to engage the member at the intake opening to turn on the supply of motive fluid to the conduit and maintain the motive fluid turned on while the operator retains his engagement with said member, and means for automatically shutting off the motive fluid when the operator releases said member.

2. In an ash conveying system, the combination of a conduit having a plurality of ash

intake openings, means for supplying motive fluid to said conduit for moving the material therethrough, means for controlling the supply of motive fluid to said conduit, including a member adjacent each ash intake opening and enabling the operator when at any one of said intake openings and while moving ash into the same to engage the member at the intake opening by his foot and turn on the supply of motive fluid to the conduit and maintain the motive fluid turned on as long as the operator retains his foot on said member, and means for automatically shutting off the motive fluid when the operator releases his foot from said member.

3. In an ash conveying system, the combination of a conduit having a plurality of ash intake openings, means for supplying motive fluid to said conduit for moving the material therethrough, means for controlling the supply of motive fluid to said conduit, including a depressible member adjacent each ash intake opening and enabling the operator when at any one of said intake openings to turn on the supply of motive fluid to said conduit by depressing the member at the intake opening and maintain the motive fluid turned on as long as the operator holds said member depressed, and means for automatically shutting off the motive fluid when the operator releases said member.

4. In an ash conveying system, the combination of a conduit having a plurality of ash intake openings, means for supplying motive fluid to said conduit for moving the material therethrough, means for controlling the supply of motive fluid to said conduit, including a spring controlled member pivotally mounted adjacent each ash intake opening and enabling the operator when at any one of the intake openings to turn on the supply of motive fluid to said conduit by operating said member and maintain the motive fluid turned on as long as the operator retains his engagement with said member, and means for automatically shutting off the motive fluid when the operator releases said member.

5. In an ash conveying system, the combination of a conduit having a plurality of ash intake openings, means for supplying motive fluid to said conduit for moving the material therethrough, means for controlling the supply of motive fluid to said conduit, including a member adjacent each ash intake opening and arranged and mounted so that the operator may when standing in front of an intake opening and while hoeing ash into the same readily engage the member at said intake opening and turn on the supply of motive fluid to the conduit and maintain the motive fluid turned on as long as the operator retains his engagement

with said member, and means for automatically shutting off the motive fluid when the operator releases said member.

6. In an ash conveying system, the combination of a conduit having a plurality of ash intake openings, a valve for controlling the supply of motive fluid to said conduit, a compressible member at each of said intake openings, means common to all of said members and connecting all of the same with said valve whereby the latter may be opened by the operator depressing any of said members and keeping the valve turned on as long as the operator holds any of said members depressed, and means for automatically closing said valve when the member is released by the operator.

7. In an ash conveying system, the combination of a conduit having a plurality of ash intake openings, a valve for controlling the supply of motive fluid to said conduit, a compressible member at each of said intake openings, an endwise movable member extending along the conduit and common to and connecting said valve with each of said compressible members, whereby said valve may be opened for turning on the supply of

motive fluid to said conduit by the operator depressing any of the compressible members and keeping the valve turned on as long as 30 the operator holds a member depressed, and means for automatically closing said valve when the member is released by the operator.

8. In an ash conveying system, the combination of a conduit having a plurality of ash intake openings, a valve for controlling the supply of motive fluid to said conduit, a spring controlled foot-operated member at each ash intake opening, a cable extending along the conduit and common to and 40 connecting said valve with all of said members, whereby the valve may be opened for turning on the motive fluid to the conduit by the operator engaging one of said members with his foot and depressing the same, 45 and means for automatically closing said valve for shutting off the motive fluid when the operator releases said member.

In testimony that we claim the foregoing as our invention, we affix our signatures, 50 this 18th day of February, A. D. 1919.

HERMAN A. POPPENHUSEN.
ARTHUR P. STRONG.
